UNITED STATES PATENT OFFICE.

WELLINGTON B. WHEELER, OF LONG BEACH, CALIFORNIA.

DESIGN FOR AN AUTO-TRAILER.

48,767.

Specification for Design.

Patented Mar. 21, 1916.

Application filed December 16, 1915. Serial No. 67,283. Term of patent 3½ years.

To all whom it may concern:

Be it known that I, WELLINGTON B. WHEELER, a citizen of the United States, residing at Long Beach, in the county of Los Angeles and State of California, have invented a new, original, and ornamental Design for Auto-Trailers, of which the following is a specification, reference being had to the accompanying drawings, forming a part thereof.

I claim:

The ornamental design for an auto trailer, as shown.

WELLINGTON B. WHEELER.
